DRAFTING MECHANISM

Paul Devaux, Maromme, France

Application February 5, 1937, Serial No. 124,315
In France August 31, 1936

4 Claims. (Cl. 19—130)

This invention is an improvement in the draft mechanism of spinning and like machines and more particularly an improvement on my Patent 1,784,659, December 9, 1930, in which a pair of small rollers, sometimes called slip-rollers, is located to control the fibers between a pair of retaining rolls and a pair of drawing or delivery rolls and is driven by a rotating permanent magnet on which the lower slip roll rests. The present invention consists chiefly in that the drive shaft, instead of being or carrying a permanent magnet, is merely a plain shaft of magnetic material separate from the drafting and retaining rolls and each small roller in contact with it is itself a permanent magnet and made effective to produce the magnetic attraction, necessary for the required driving friction by providing that its magnetic poles at the opposite end of such small roller shall have contact only with non-magnetic material, thereby avoiding short-circuiting of the magnetic lines of force with consequent impairment of the friction drive.

Further characteristics of the invention will be set forth in the following description.

In the accompanying drawings, which are given solely by way of example:

Fig. 1 is a vertical cross-section, on the line 1—1 of Fig. 2, of a mechanism according to the invention (shown in heavy lines) in position upon a continuous spinning machine.

Fig. 2 is a corresponding plan view, the usual upper cylinders being removed.

Figs. 3, 4 and 5, 6 show two modifications in sectional and in plan view.

In the embodiment shown in Figs. 1 and 2, the drawing head for spinning purposes comprises, in the known manner, delivery rollers 1 and 1^a, intermediate or retaining rollers 2 and 2^a, and feed rollers 3 and 3^a.

The bearing parts of the lower roller 1 rest upon the frame 4 of the drawing head. The lower rollers 2 and 3 bear upon a member 5, adjustable in position relatively to the roller 1, by sliding on the frame 4. The upper rollers 2^a and 3^a have their journals located in grooves in the arms of caps 6, which are pivoted to a bar 7.

As to the roller 1^a, its journals are located in grooves formed in the blocks 8, which are secured by screws 9 to the cap arms 6.

In order to support the fibres of the roving as near as possible to the nip of the delivery rollers 1—1^a, there is mounted between the rollers 1—1^a and 2—2^a a set consisting of two rollers 10 and 11, whose diameter is small as necessary in order that their line of contact shall be at as short a

distance as may be desired from the nip of the delivery rollers.

The roller 10 is a permanent magnet. The positive rotation of said magnet 10 at the desired speed is obtained without torsion or bending, due to the fact that said magnet rests on a driving shaft 40 having the normal diameter of the rollers used in spinning machines. Said shaft 40 is driven at its end or in any other manner in a direction opposite to the direction of rotation of the rollers 1, 2 and 3.

The roller 11 and the magnet 10 are preferably each of a length which corresponds to two spindles of a continuous machine, that is to say, each is local to one of the spaces between the frame 15 members.

In this case, each magnet element 10, and the corresponding pressure element 11, are held in place by journals engaged in grooves 17 formed in the members 18, which consist of non-magnetic material.

Each member 18 forms a fork in order to give passage to the supporting arm of the block 8 in which is journaled the roller 1^a, and the said fork bears upon the edges of said arm in order to avoid any lack of parallelism between the elements 10 and 11, relatively to the usual rollers.

Each member 18 can be secured to one of the arms 6 by any suitable means, such as a screw 19 passing through a slot 20 in the member 18.

The shaft 40 and the magnet 10 may be smooth or fluted, striated, milled, etc.

The effect of confining the ends of the small roller 10 in the grooves 17 of the non-magnetic roll-holders 18 is to block off and greatly reduce the flow of magnetic lines of force through the frame members and adjacent rolls, thereby confining practically the whole magnetic flux to the small roll itself and the portion of the drive shaft that is co-extensive with it. This concentration is indispensable to the required magnetic attraction for friction-driving purposes.

The pressure with which the upper roll 11 bears upon the roving is subject to control by selecting the amount of magnetic material in it, but as the required pressure is only slight this roller is made of magnetic material with a non-magnetic covering such as brass or leather of a selected thickness, spacing it away from the lower roller to the extent desired for the particular pressure wanted. With such magnetic insulation on the roll 11 there is only an un-objectionable shunting of the magnetic field away from the drive shaft.

In the embodiment shown in Figs. 1 and 2, the material under treatment is supported and con-

ducted by the magnet 10, whose surface speed is the same as that of the shaft 40, whatever be their respective diameters, and thus the said shaft 40 should give to the magnet 10 the speed which is to be imparted to the material.

5 In this construction, the spacing between the nips of the said magnet 10 and that of the roller 2, is determined by the diameter of the shaft 40 and of the said roller 2, and although this spacing 10 is reduced to 22 mm. (which as a rule will perfectly control the fibres at this point) in the case of usual diameters of 10 mm. for the magnet 10, 19 mm. for the roller 2, and 16 mm. for the shaft 40, it may be desired, in certain special 15 cases, to have smaller spacings but at the same time to obtain a progressive surface speed from the roller 2 to the roller 10.

For this purpose, it is possible to reduce the 20 diameters of the rollers 2 and 40 and to leave them independent, but the choice of said diameters is limited by the strength of these rollers which is indispensable for their durability and for their manipulation during cleaning.

As shown in Figs. 3 and 4 on the one hand, 25 and Figs. 5 and 6 on the other hand, it is possible to comply with such requirements and to obtain these results, by using the shaft 40 to support and to drive two magnets disposed along the longitudinal direction of the machine.

30 Thus in the embodiments shown in Figs. 3 and 4, the cylindrical shaft 40, whose diameter is 16 mm. for instance, supports and drives a magnet 10 of 10 mm. diameter, for instance, upon its whole length, said magnet having the same circumferential speed as the shaft, and also a magnet 10^a whose parts in contact with the shaft 40 have a larger diameter than that of the parts 35 of this magnet which operate upon the material (for instance 13 mm. and 12 mm.). Hence the 40 magnet 10 has a circumferential speed of 1.083 in the present construction, when the magnet 10^a has a circumferential speed of 1 for the same speed of the shaft 40.

45 In the embodiment shown in Figs. 5 and 6, the shaft 40, which has for instance 18 mm. diameter in its parts which support and drive the magnet 10, has a smaller diameter (for instance 14 mm.) in its parts which support and drive the magnet 10^a; on the other hand, the 50 magnet 10 has for instance 10 mm. diameter upon its entire length, and the magnet 10^a has 16 mm. in its parts in contact with the shaft 40, and 10 mm. in its parts acting upon the material. In this case, the circumferential speed of the magnet 10 is 2.05, when the magnet 10^a has a circumferential speed of 1 for the same speed of 55 the shaft 40.

60 In the constructions shown in these Figures 3-4 and 5-6, the distance between the nips of the roller 1 and of the magnet 10, as well as the distance 65 between the nips of magnets 10 and 10^a, are for instance 16 mm., while at the same time permitting the use of a load pressure or a pressure which is free but is sufficiently heavy, in many cases, by means of the roller 2^a.

65 Such distances may be further reduced if so desired, by reducing the diameter of the magnet 10 and of the roller 11, etc. In these constructions the driving friction between the shaft 40 and the intermediate roll 10^a is susceptible of increase as desired by increasing the weight of the 70 top roll 2^a so that the magnetic attraction of 10^a

to 2^a need not be relied upon for the entire friction and it is not of so great consequence if some of the lines of force of the roll (10^a) are shorted to the top roll 2^a or the frame.

These examples alone will give an idea of the 5 number of possible combinations.

In these devices, the rollers 2^a, which are not shown in plan view, are machined in order to fit upon the bosses of the magnet 10^a and to bear freely upon the parts of the said magnet which 10 act upon the material.

It will be observed that the material under treatment, such as cotton, wool or the like, will not be subjected to any effect from the magnets, as these are by no means charged with electricity, 15 but have simply received, once for all, the magnetic induction, whose flux has no effect whatever upon such material.

The said devices and their modifications as above described are chiefly adapted for use with 20 two spindles of a continuous machine or four spindles of a self-acting machine; however, they may be arranged, for reasons of economy, for four or more spindles for continuous machines or eight or more spindles for self-acting machines. 25

The several devices herein described and their modifications are applicable to the existing machines for the preparation and the spinning of cotton, wool, and the like, as well as to all such 30 machines which may be further constructed.

Obviously, the said invention is not limited to the embodiments herein described and represented, which are given solely by way of example.

Having now described my invention what I 35 claim as new and desire to secure by Letters Patent is:

1. In drawing mechanism for spinning and like machines, of the kind including small rollers located to have controlling contact with the fibers passing from pairs of retaining rolls to pairs of drawing rolls and close to the bite of the latter, said rolls being supported at intervals in frame members and said small rollers being local to the spaces between said members and held therein to rotate on fixed axes and being driven by a common rotary drive-shaft by virtue of their frictional contact therewith, the improvement which consists in each said small fiber-contacting roller being a permanent magnet and said drive-shaft in contact therewith being of magnetic material and the parts contacting the magnetic poles at the opposite ends of said small roller being of non-magnetic material adapted for reducing short-circuiting of the magnetic field of said small roller through said frame members and the other rolls. 50

2. The structure of claim 1 having an upper small roller of magnetic material, resting on the lower small roller and covered with non-magnetic material. 60

3. The structure of claim 1 in which the lowermost of the two retaining rolls is also a permanent magnet frictionally driven by said drive-shaft. 65

4. The structure of claim 1 in which the bottom retaining roll is also a permanent magnet and is provided with parts of larger diameter having frictional driving contact with said driving-shaft. 70
